UNITED STATES PATENT OFFICE

ROBERT P. HARVEY, OF SPRINGFIELD, MASSACHUSETTS, ASSIGNOR TO THE FISK RUBBER COMPANY, OF CHICOPEE FALLS, MASSACHUSETTS, A CORPORATION OF MASSACHUSETTS

CALENDER CONSTRUCTION

Application filed July 9, 1927. Serial No. 204,646.

This invention relates to multiple roll calenders, particularly such as are intended for use in rubber manufacture. One object of the invention is to provide an adjustment for calender rolls adapted to calenders having any desired number of rolls. A further object is to provide novel and simple means for adjusting the spacing of any adjacent pair of calender rolls without affecting the adjustment of the remaining rolls.

Referring to the drawings:

Fig. 1 is a diagrammatic vertical section through a four-roll rubber calender embodying my invention; and

Fig. 2 is a diagrammatic view showing the application of the invention to a six-roll calender.

Referring to the construction shown in Fig. 1, the calender rolls are mounted upon a frame 10, there being one of these frames at either end of the calender as is usual. Journaled for rotation in these frames is a roll 11, the axis of which remains fixed. Above this fixed roll is mounted a roll 12 journaled in boxes 13 made vertically adjustable by means of screws 14. At the bottom of the calender is a roll 15 journaled in boxes 16 vertically adjustable by screws 17. The adjustment of these latter two rolls may be made in any standard manner. Mounted above roll 15 is a roll 18 journaled in boxes 19 having arcuate faces sliding in ways 20 in the frames. The surfaces of the boxes 19 and of the ways 20 are formed on arcs having as an approximate center the axis of roll 15. By means of screws 21 and 22 the position of each box 19 can be varied and maintained in adjusted position in the ways 20.

As the calender shown is suitable for the manufacture of so-called weftless cord fabric as well as for the production of rubber sheets, a comb 23 has been shown together with a roll 24 adapted to receive a sheet of cords 25 arranged in a spaced relation and press them against a rubber sheet upon roll 11. In oper-

ation a feed of rubber 26 is placed between rolls 11 and 12 and a feed 27 between rolls 15 and 18. The upper two rolls form the rubber from feed 26 into a sheet 28 while the lower two rolls form the rubber from feed 27 into a sheet 29, the two sheets thus formed being joined into one composite sheet, together with cords 25 if desired, between the rolls 11 and 18. It will be understood that the rolls may be rotated in the direction of the arrows by any suitable or standard gearing, the nature of which is not affected by the method of adjustment forming my present invention.

It will be observed that the roll 18 is offset from the line of centers of rolls 11 and 12. This is desirable although not absolutely necessary as it permits the adjustment of journal boxes 19 in ways 20 to have a greater effect in varying the spacing of rolls 11 and 18 than would be the case were the rolls all in line.

The adjustment of the spacing between rolls 11 and 12 and between rolls 15 and 18 is accomplished in the usual manner by screws 14 and 17 respectively. Roll 18, however, being moved by the adjusting screws 21 and 22 in an arcuate path having as an approximate center the axis of roll 15, does not in its movement of adjustment vary the spacing between itself and roll 15, but only the spacing between itself and roll 11. By this means, which requires a minimum of calender parts, the spacing between any two adjacent rolls may be varied without changing the adjustment between any other two rolls.

In Fig. 2 I have shown diagrammatically the application of my invention to a calender having six rolls. The application of the invention to calenders of greater or less number of rolls than this will be apparent to those skilled in the art. In the example of Fig. 2 the roll 31 is fixed. That is to say, its axis is non-adjustable. The roll 32 is vertically adjustable in the standard man-

ner. Roll 33 is likewise vertically adjustable in the standard manner. Roll 34 is adjustable upon an arc having as an approximate center the axis of roll 33. Roll 35 is similarly adjustable about the approximate center of roll 34 and roll 36 is adjustable about the approximate center of roll 35. The adjustment of any adjacent pair of rolls in this construction can be carried on without affecting the spacing of any other pair of rolls.

In both the four and six roll constructions I have spoken of certain of the rolls being capable of adjustment in an arcuate path having as an approximate center the axis of an adjacent roll. It is preferable to keep the center of this arc as nearly as possible coincident with the axis of the adjacent roll, but due to the fact that the adjacent roll itself has a slight transverse movement of adjustment it will be impossible to maintain the desired relation with mathematical exactness at all times. Since, however, the thickness of the rubber sheets generally produced is only a matter of a very few hundredths of an inch, the coincidence of the centers will be so close that the movement of the arcuately adjustable roll will produce no appreciable effect upon its spacing from the roll about whose axis it swings.

Having thus described my invention, I claim:

1. A rubber calender having a plurality of rubber sheeting rolls one of which has a fixed axis, means for adjusting transversely the axis of one adjacent roll, means for adjusting transversely the axis of a roll remote from the fixed roll, and means for adjusting the axis of the roll between the fixed roll and the remote roll in an arc having the axis of the remote roll as an approximate center.

2. A rubber calender comprising a plurality of rubber sheeting rolls at least one of said rubber sheeting rolls being constrained for transverse movement in an arcuate path having as an approximate center the axis of an adjacent rubber sheeting roll.

3. A four roll calender having the axis of one intermediate roll fixed, means for adjusting the adjacent end roll toward and away from the fixed roll, means for adjusting the remote end roll transversely of its axis, and means for adjusting the second intermediate roll in an arcuate path having as an approximate center the axis of the remote end roll.

4. A four roll calender having the line of centers of the upper two rolls substantially vertical and the line of centers of the bottom two rolls substantially vertical but offset from the line of centers of the upper two rolls, means for adjusting the top roll vertically, means for adjusting the bottom roll vertically, and means for adjusting one of the intermediate rolls in an arcuate path

having as an approximate center the axis of the adjacent end roll.

5. A rubber calender having a plurality of rubber sheeting rolls with certain of the rubber sheeting rolls offset from the line of centers of certain other of the rubber sheeting rolls, and means for adjusting one of the offset rubber sheeting rolls in an arcuate path having as an approximate center the axis of an adjacent rubber sheeting roll.
